UNITED STATES PATENT OFFICE

2,436,207

ELECTRIC WINDING

Franklin R. D'Entremont, Lynn, Mass., assignor
to General Electric Company, a corporation of
New York

Application December 29, 1945, Serial No. 638,056

18 Claims. (Cl. 175—358)

1

This invention relates to electrical induction apparatus and more particularly to improvements in current transformers.

In certain transformers of the above-mentioned type it is necessary to have a multi-turn primary winding whose current carrying conductor is of large cross sectional area. Such transformers often have a two legged core and in order to improve the characteristics of the transformer it is desirable to have its primary winding and its secondary winding each divided into two coils which are on the different legs of the core. One way of winding a two coil primary winding of heavy bar or strap conductor forms the subject matter of Patent 2,374,018, granted April 17, 1945, on an application of Harold E. Johnson and assigned to the present assignee. While the Johnson winding is very satisfactory for certain applications, it requires that the heavy strap conductor be very accurately pre-cut as to length and the winding must be made very carefully if the terminals are to be in proper alignment and have the proper spacing. These latter factors are important when the core and coil assembly of the transformer is to be mounted in a preformed casting and also when the transformer is to be interchangeable with others.

In accordance with one of the features of a preferred form of this invention the primary winding of a current transformer consists of serially connected duplicate separately and specially wound coils. These coils are characterized by having one end or terminal split into two parts having normally parallel surfaces on opposite sides of the coil so that the coils can readily be fitted together and aligned before their electrical interconnections are made permanent. These permanent electrical connections are typically made by brazing.

In accordance with another feature of the invention the two coils of the primary winding are surrounded by a tight reinforcing band so as to prevent distortion of the coils under short circuit conditions and so as mechanically to strengthen the transformer structure. This reinforcing band may be made of steel and as it surrounds the coils on the outside it does not link the core flux and does not constitute a short circuited conducting turn with respect to the core flux. This band also serves as a shield to reduce the flux entering the core from a return conductor.

An object of the invention is to provide a new and improved electrical induction apparatus.

Another object of the invention is to provide a strong compact current transformer for heavy current service.

A further object of the invention is to provide a new and improved multi-turn current transformer primary winding of heavy current carrying capacity.

2

The invention will be better understood from the following description taken in connection with the accompanying drawing and its scope will be pointed out in the appended claims.

5 In the drawing Fig. 1 is a partially broken away side elevation view of a transformer embodying my invention, Fig. 2 is a sectional view of the transformer taken on line 1—1 of Fig. 1, Fig. 3 shows the double coils of the primary winding of the transformers shown in Figs. 1 and 2 before they are interconnected, Fig. 4 shows how the primary winding of the transformers is formed by interconnecting the coils shown in Fig. 3, Fig. 5 shows a modified primary winding construction having three turns, and Fig. 6 shows the double coils from which the primary winding of Fig. 5 is made.

10 Referring now to the drawing and more particularly to Fig. 1, the transformer is shown as comprising a two legged core 1 of any suitable type, it being shown by way of example as being of the wound type. Surrounding the two legs of the core 1 are coils 2 and 3 which together constitute the secondary winding of the current transformer. Surrounding the secondary coil 2 is a primary winding coil 4 and surrounding the secondary winding 3 is a primary winding coil 5. The primary winding coil 4 is provided with a heavy terminal bar or strap 6 and similarly the primary winding coil 5 is provided with a heavy terminal bar or strap 7.

15 As shown in both Figs. 1 and 2, the primary winding coils are made of relatively wide and thin strap conductors which are embedded in suitable insulation 8.

20 Wrapped tightly around the outside of the two primary coils 4 and 5 is a reinforcing band or strap 9 which may be of steel. The purpose of this band is to prevent deformation of the primary winding under conditions in which extra large currents flow through the primary winding. The magnetic effect of such currents is to tend to make the coils assume a circular cross section, and then to expand, and if they were allowed to do 25 this their conductors would pull away from the insulation 8 and thereby effectively destroy the transformer. It will be observed that the band 9 in surrounding the entire core and coil structure does not link any of the transformer flux, and thus it does not in any way affect the electrical characteristics of the transformer.

25 The primary winding, as will be seen from Fig. 2, is a two-turn four-conductor winding. The details of this winding are shown more clearly in Figs. 3 and 4. Considering first the coil 4 shown in Fig. 3, it will be seen that there are four radially superposed conducting bands or straps. All of these straps have one end aligned with an edge of the terminal 6, and they are electrically connected to the terminal 6 in any suitable way such

as by brazing. The four conductors then make substantially one complete turn together, this turn being generally rectangular in cross-section. At the point 10 the outermost conductors, considered collectively as 11, terminate while the two innermost conductors, which will be considered collectively as 12, continue for substantially another one-half turn to the point 13 which it will be observed is substantially diametrically opposite to the point 10 and thus is one-half turn away therefrom. At point 13 the innermost conductors 12 project tangentially away from the coil to form a straight terminal surface 14 which, although on the opposite side of the winding from the end 10 of the outer straps 11, is generally parallel with the outer surface of the straps 11. A strip of insulation 15 is inserted between adjacent strips which have a potential difference of 1 turn.

It is not essential to have four conductors as illustrated and it will be obvious to those skilled in the art that so far as my invention is concerned the double conductors 11 and 12 can be single straps or conductors if desired. Furthermore, as far as the principle of my invention is concerned, it is unnecessary to have the conductor stranded at all, and it can be solid up to the point 10 where the coil divides into the outer short part 11 and the inner long part 12. Thus the coil 4 is characterized by having three terminals 6, 11 and 14, the latter two being the respective ends of two effectively parallel parts of the coil which have a common terminal 6.

The coil 5 is preferably a duplicate of the coil 4. Therefore, with the exception of its terminal 7, its parts which correspond to the parts of coil 4 are given corresponding primed reference numerals. Coil 5, however, has been rotated 180 degrees on its axis, relative to the position of coil 4 so that the terminals 6 and 7 of these coils extend away from each other as in Figs. 1 and 2. It will be observed that the tangentially extending projections 14 and 14' of the two coils are parallel to each other, and are also parallel with the surfaces 11 and 11' so that these coils may be slipped together as shown in Fig. 4. However, it is necessary to provide a piece of insulation 16 between the coils because their adjacent conductors are not at exactly the same potential and in fact are separated by the potential of one-half turn. In Fig. 4 the coils have been pushed together so that the part 14 is in overlapping contact with the part 11', and the part 14' is in overlapping contact with the part 11 and permanent connections may be made between these overlapping contacting surfaces by brazing them together. However, before these permanent connections are made there is considerable freedom of movement so that the terminals 6 and 7 can be very accurately and easily prealigned even though there are substantial manufacturing tolerances or variations in the ends of coils. It will also be observed that the coils are fastened together at their outside surfaces, and not in between them so that it is relatively easy to make the brazing operation or its equivalent. In performing the brazing operation the ends or parts to be joined are bent outwardly as indicated by the dotted showing at the top of Fig. 4. The parts can then readily be clamped between electrodes (not shown) which provide the heating current.

The winding shown in Fig. 4 will readily be seen to have mechanical symmetry. It also has electrical symmetry between the terminals 6 and 7, the outer conductors 11 of the coil 4 which

make one-half an electrical turn with respect to the core are in series with the inner conductors 12' of the coil 5 which make one and one-half electrical turns with respect to the core so that the total of these turns of this series connection is two turns. Likewise between the two terminals 6 and 7 the inner conductors 12 of the coil 4, which make one and one-half electrical turns with respect to the core, are in series with the outer conductors 11' of the coil 5, which make one-half an electrical turn with respect to the core, so that again this part of the winding has two electrical turns. Therefore, in a sense, the winding between its terminals 6 and 7 consists of two parallel paths, each having two electrical turns, one being made of one-half turn plus one and one-half turns and the other being made of one and one-half turns plus one-half turn.

In the modification shown in Figs. 5 and 6 the winding has three electrical turns. This winding is also made up of duplicate coils 17, which are shown, by way of example, as also having four conductors or strands. These conductors are attached to terminals 6 and 7, as in the previous figures, but they make one and one-half mechanical turns together up to the point 18 where they divide one part or pair 19 extending tangentially away from the coil and its main terminal and the other part or pair 20 extending on for substantially another one-half mechanical turn and ending along the surface 21 on the opposite side of the coil. As in the two turn coil shown in Figs. 1 through 4 inclusive, insulation 22 is inserted between the adjacent turns of the winding but it is unnecessary to have an insulating piece corresponding to the piece 16 in Figs. 3 and 4 between the coils 17 because the parts 19 and 21 are all at the same potential. Fig. 5 shows how the two coils 17 are interfitted to form a two coil winding. The surfaces 19 and 21 are of course permanently interconnected in any suitable manner after the coils have been properly spaced and aligned. In Figs. 5 and 6, the two coils each have one and one-half electrical turns so that the total electrical turns of the winding is three.

While there have been shown and described particular embodiments of this invention, it will be obvious to those skilled in the art that various changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

1. An electric coil having three terminals one of which is a common terminal with respect to two effectively parallel paths between it and the remaining pair of terminals, said pair of terminals having substantially mechanically parallel surfaces, one of said pair of terminals being a projection extending generally tangentially away from a side of said coil, the other of said terminals being on the outer surface of the said coil on the diametrically opposite side thereof.

2. An electric coil having three terminals one of which is a common terminal with respect to two effectively parallel paths between it and the remaining pair of terminals, said paths having an unequal number of electrical turns, said pair of terminals having substantially mechanically parallel surfaces, one of said pair of terminals being a projection extending generally tangentially away from a side of said coil, the other of

said terminals being on the surface of said coil on the opposite side thereof.

3. An electric coil having three terminals one of which is a common terminal with respect to two effectively parallel paths between it and the remaining pair of terminals, said paths having an equal number of electrical turns, said pair of terminals having substantially mechanically parallel surfaces, one of said pair of terminals being a projection extending generally tangentially away from a side of said coil, the other of said terminals being on the surface of the said coil on the opposite side thereof.

4. An electric coil having three terminals one of which is a common terminal with respect to two effectively parallel paths between it and the remaining pair of terminals, each of said paths having the same odd number of one-half electrical turns, said pair of terminals having substantially mechanically parallel surfaces, one of said pair of terminals being a projection extending generally tangentially away from a side of said coil, the other of said terminals being on the surface of said coil on the opposite side thereof.

5. An electric coil having three terminals one of which is a common terminal with respect to two effectively parallel paths between it and the remaining pair of terminals, each of said paths having one and one-half electrical turns, said pair of terminals having substantially mechanically parallel surfaces, one of said pair of terminals being a projection extending generally tangentially away from a side of said coil, the other of said terminals being on the surface of said coil on the opposite side thereof.

6. An electric coil having three terminals one of which is a common terminal with respect to two effectively parallel paths between it and the remaining pair of terminals, one of said paths having one electrical turn more than the other one, said pair of terminals having substantially mechanically parallel surfaces, one of said pair of terminals being a projection extending generally tangentially away from a side of said coil, the other of said terminals being on the surface of said coil on the opposite side thereof.

7. An electric coil having three terminals one of which is a common terminal with respect to two effectively parallel paths between it and the remaining pair of terminals, one of said paths having one and one-half electrical turns and the other one having one-half an electrical turn, said pair of terminals having substantially mechanically parallel surfaces, one of said pair of terminals being a projection extending generally tangentially away from a side of said coil, the other of said terminals being on the surface of said coil on the opposite side thereof.

8. An electric winding comprising a pair of the coils defined in claim 3, said coils being arranged with the surfaces of the respective pairs of terminals parallel with each other, each tangentially extending terminal being in overlapping electrical contact with the surface terminal of the other coil whereby said coils are serially connected and said winding has both mechanical and electrical symmetry.

9. An electrical coil of flatwise bent strap conductor one of whose ends has a terminal and the other of whose ends is split into two parts of different lengths, one part having an end which projects generally tangentially of said coil away from its terminal end, the other part having an end on the surface of said coil substantially one-

6 half of a mechanical turn away from where the first part tangentially projects away from said coil.

10. An electric winding comprising a pair of coils defined in claim 9, said coils being laterally side by side with their terminal ends forming opposite mechanical and electrical ends of the winding, the tangentially projecting part of each coil being electrically connected to the other part of the other coil whereby said coils are connected in series and said winding has mechanical and electrical symmetry.

11. A winding comprising serially connecting coils, each coil having a terminal end and an end for a connection to the other coil, said last-mentioned ends being split into two parts one of which makes substantially one-half a mechanical turn more than the other, the part making the fewer mechanical turns having a generally tangentially extending projection, each projecting part being electrically connected to the part of the other coil which makes the greater number of mechanical turns.

12. A winding comprising duplicate serially connected coils for respectively linking two winding legs of a magnetic core, each coil having a terminal end and an end for connection to the other coil, said last-mentioned ends being split into two parts one of which makes substantially one-half a mechanical turn more than the other, the part making the fewer mechanical turns having a generally tangentially extending projection, each projecting part being electrically connected to the other part on the other coil which makes the greater number of mechanical turns whereby said winding is electrically and mechanically symmetrical.

13. A winding comprising duplicate serially connected coils of radially superposed flatwise bent conductors for respectively linking two winding legs of a magnetic core, each coil having a terminal end and an end for connection to the other coil, said last-mentioned ends being split into two parts one of which makes substantially one-half mechanical turn more than the other, the part making the fewer mechanical turns having a generally tangentially extending projection, each projecting part being electrically connected to the other part on the other coil which makes the greater number of mechanical turns whereby said winding is electrically and mechanically symmetrical.

14. A winding as in claim 12 in which each coil has the same odd number of half electrical turns.

15. A winding as in claim 12 in which each coil has one and one-half electrical turns.

16. A winding comprising serially connected coils, each coil having a terminal end and an end for connection to the other coil, said last-mentioned ends being split into two parts one of which makes substantially one-half of a mechanical turn more than the other, the part making the greater number of mechanical turns having a generally tangentially extending projection, each projecting part being electrically connected to the part on the other coil which makes the fewer number of mechanical turns.

17. A substantially rectangular cross section coil for a duplicate coil wound primary winding for a current transformer comprising, in combination, a terminal piece, at least two radially superposed strap conductors electrically connected at one end to said terminal piece, the inner 70 of said strap conductors making one and one-

half mechanical turns and extending tangentially away from said coil at its other end, the outer of said strap conductors making one mechanical turn and having its other end at the surface of said coil.

18. A substantially rectangular cross section coil for a duplicate coil wound primary winding for a current transformer comprising, in combination, a terminal piece, at least two radially superposed strap conductors electrically connected at one end to said terminal piece, the inner of said strap conductors making two mechanical turns and having its end at the surface of said coil, the outer of said strap conductors making one and one-half mechanical turns and extending tangentially away from said coil at its other end.
